HINGED LAST

Fred W. Stuart, Beverly, Mass., assignor to Maxwell A. Stuart, Beverly, Mass.

Application April 9, 1934, Serial No. 719,664

2 Claims. (Cl. 12—136)

This invention relates to hinged lasts and its object is to provide a last of this type which shall be rigidly supported in expanded position by a metallic link against heavy pressure exerted upon the tread face of the shank of the last in various shoemaking operations, such, for example, as sole leveling. I have discovered that a link may be secured in the heel part of the last so that it will swing through a limited arc, corresponding to the collapsing movement of the last, and be positively arrested in both of its limiting positions by cooperating anchor pins, so that the link acts as a rigid strut or cantilever beam for the support of the toe part of the last. Pressure on the tread face of the toe part of the last may thus be resisted as a longitudinal stress in the link and a shearing stress upon the anchor pins, instead of tending to break down cooperating wooden faces or pull out wood screws from hinge parts. It will thus be seen that by the construction of my invention I am enabled rigidly to support the two parts of the last in the relative position which they assume either in expanding or in collapsing the last.

Preferably and as herein shown, the connecting link of my improved last is provided with a spring element which tends at all times to pull the last parts forcibly toward each other, thus tending to take up wear which may develop over an extended period of use and at the same time to set up and maintain a degree of frictional engagement between the two parts of the last sufficient entirely to obviate accidental displacement thereof and to hold the parts in either expanded or collapsed condition, as desired by the workman.

These and other features of the invention will be best understood and appreciated from the following description of a preferred embodiment thereof, selected for purposes of illustration and shown in the accompanying drawing, in which

Fig. 1 is a view of the last in side elevation with portions broken away to expose the hinge construction;

Fig. 2 is a sectional view on the line 2—2 of Fig. 1;

Fig. 3 is a view in perspective of the connecting link;

Fig. 4 is a sectional view showing the hinge parts in the collapsed position of the last; and

Fig. 5 is a similar view showing an intermediate position of the last parts.

The heel part 10 of the last is herein shown as provided with the usual comb plate 12, of fibre or the like, and the usual metal heel plate

14. It is also provided with a forwardly projecting curved hinge element 16 which, it will be understood, extends for the full width of the heel part. The toe part 18 is provided with a correspondingly shaped concave socket 20 interfitting with the surface of the hinge element 16. This hinge connection between the two parts of the last permits relative pivotal movement thereof about a fixed axis coinciding with the center of curvature of the interfitting faces. The hinge element 16 of the heel part is provided with a transverse anchor pin hole at this center of curvature. When the last is in expanded position, the tread surface of the heel part and the tread surface of the toe part coincide, as do the lower edges of these two parts, as shown in Fig. 1, and when the last is moved into collapsed position these edges are separated, as shown in Fig. 4.

The adjacent faces of the heel and toe parts of the last are slotted or grooved in registration with each other to receive a metallic link 22 which holds them together while permitting the pivotal movement already explained. The link 22 is provided with an intermediate transverse slot 24 which is located in line with the axis of movement of the last parts and through which passes an anchor pin 32 which is set in the heel part 10 of the last. At its rear end the link 22 is provided with an open ended slot 26, the inner end of which forms a hole for the reception of a second anchor pin 30 which extends through the heel part in a position at the rear of the anchor pin 32. The slot 26 is enlarged at its outer end and provided with oppositely disposed recesses which constitute a socket for a plurality of transverse spring leaves 28. These are piled up in superposed relation, or in a pack, and slipped transversely into the socket in the link 22 thus provided. They close the inner end of the slot 26, thus forming a hole for the reception of the anchor pin 30, and they are free to be bowed rearwardly into the open end of the slot 26 by the pressure of the anchor pin 30. At its forward end the link 22 is connected to the toe part 18 of the last by an anchor pin 34.

It will thus be seen that the link 22 is pivotally connected adjacent to its opposite ends by the anchor pins 30 and 34 to the heel and toe parts respectively of the last. In all positions of these parts, the spring leaves 28 are maintained under stress and tend, therefore, powerfully to pull the two parts of the last toward each other, that is, the spring leaves 28 react against the anchor pin 30 to pull the anchor pin 34 rearwardly. The link thus acts to maintain at all times an appreciable

and uniform frictional pressure between the interfitting curved faces of the projection 16 and the socket 20.

When the last occupies its expanded position, with the tread face edges of its toe and heel portions contacting, as shown in Fig. 1, the anchor lock pin 32 just clears the upper end of the slot 24 of the link. It is in this condition, and with the toe supported by a rest engaging it at some such position as indicated at A, that the shank part of the last is subjected to leveling pressure in the shoemaking process and this pressure tends to break the back of the last about the tread-face edges as a fulcrum. It will be seen that such pressure exerted on the tread face of the last is resisted by tension in the link 22 between the anchor pin 34 and the anchor lock pin 32. In other words, the leveling pressure on the shank of the last tends to separate the pins 34 and 32 but this separating movement is positively resisted in the link 22 by the engagement of the pin 32 with the side wall of the slot 24.

There is a special relationship between the end of the transverse slot 34 and the anchor lock pin 32 when the last is in expanded position. In general use it sometimes happens that the meeting edges of the two portions of the last at the tread face become battered or upset in use. As herein shown, the end of the slot 24 lies just far enough beyond the pin 32 in the normal expanded position of the last to act as a reinforcement or as a positive limit stop in case any such deformation of these meeting edges should occur. This action of the anchor lock pin in cooperation with the end of the slot 24 is in addition to its function already explained in bearing against the side wall of the slot so that the forward portion of the link acts as a solid inextensible connection resisting movement of the last parts in a direction to break the back of the last.

It has been explained that the spring leaves 28 are maintained at all times under tension. It will be observed that the position of maximum tension in the spring leaves corresponds to the position of the last parts shown in Fig. 5, wherein the three anchor pins are arranged in a straight line. In this position there is the maximum distance between the anchor pins 30 and 34. This distance decreases slightly as the forepart is moved either into expanded position, as shown in Fig. 1, or collapsed position, as shown in Fig. 4.

The natural tendency of the springs is, therefore, to maintain the last in one condition or the other, which is very desirable from the standpoint of the manufacturer.

My improved last may be assembled with great accuracy and convenience in manufacture. Having assembled the spring leaves 28 in the link 22, the latter is slipped into its groove or slot in the parts of the last and then the anchor pins 30, 32 and 34, which, as shown in Fig. 2, are provided with taper ends, are driven into place. In this operation the spring leaves 28 are deflected, as already explained, the frictional engagement of the last parts is established and the curved faces of the last parts are maintained at all times under continuous and substantial pressure of engagement.

Having thus described my invention, what I claim as new and desire to secure by Letters Patent is:

1. An improved last comprising toe and heel parts having cooperating curved faces shaped to permit said parts to swing on each other, and a metal connecting link having a longitudinal slot in one end and a circular hole in the other, a pack of superposed spring leaves located in the link and extending transversely across the outer end of said longitudinal slot, and a pin having a taper end which has been forced through one part of the last and said slot to flex said pack as a whole and maintain the leaves thereof flexed at all times, thereby holding the curved faces of the last parts under continuous and substantial pressure.

2. An improved last comprising fore and rear parts having interfitting curved surfaces shaped to permit the parts to swing on each other, and a metal connecting link having a longitudinal slot in its rear end and a circular hole in its forward end for connection with the forepart of the last, a pack of superposed spring leaves located in the link and extending across the rear end of the slot therein, and a pin having a taper end which has been driven through the rear part of the last and the slot to flex said pack as a whole and maintain the leaves thereof flexed at all times, thereby holding the curved faces of the last parts under continuous and substantial pressure in all positions thereof.

FRED W. STUART.
